United States Patent Office

Des. 201,781
Patented July 27, 1965

201,781

CARRYING CASE

John Cuccio, Westport, and Reginald R. Gallant, Bristol, Conn., assignors to Underwood Corporation, New York, N.Y., a corporation of Delaware

Filed Oct. 15, 1963, Ser. No. 76,991

Term of patent 14 years

(Cl. D87—5)

The side not shown is substantially a mirror image of the side shown, while the bottom of the case, not shown, is substantially plain and unornamented.

We claim:

The ornamental design for a carrying case, as shown and described.
